DESIGN FOR AN ELECTRIC PORTABLE RUBBING MACHINE OR THE LIKE

Stephen A. Crosby and Peter Zasadny, Chicago,
Ill., assignors to Sterling Tool Products Com-
pany, a corporation of Illinois

Application September 28, 1946, Serial No. 133,648

Term of patent 14 years

(Cl. D9—2)

To all whom it may concern:

Be it known that we, Stephen A. Crosby and Peter Zasadny, citizens of the United States, residing at Chicago, county of Cook, and State of Illinois, have invented a new, original, and ornamental Design for an Electric Portable Rubbing Machine or the like, of which the following is a specification, reference being had to the accompanying drawings, forming a part thereof, in which:

Figure 1 is a side elevational view of an electric portable rubbing machine or the like showing our new design; Figure 2, a top plan view thereof; and Figure 3, a front elevational view of the same.

We claim:

The ornamental design for an electric portable rubbing machine or the like, as shown.

STEPHEN A. CROSBY.
PETER ZASADNY.
